United States Patent Office.

FREDERICK CAJAR, OF NEW YORK, N. Y., ASSIGNOR TO HIMSELF
AND JAMES ANDERSON, OF SAME PLACE.

Letters Patent No. 83,360, dated October 27, 1868.

IMPROVEMENT IN SPRINGS.

The Schedule referred to in these Letters Patent and making part of the same.

To all whom it may concern:

Be it known that I, FREDERICK CAJAR, of the city, county, and State of New York, have invented a new and useful Improvement in Springs; and I do hereby declare that the following is a full, clear, and exact description thereof, which will enable others skilled in the art to make and use the same, reference being had to the accompanying drawings, forming part of this specification.

This invention relates to improvements in springs, the object of which is to construct them in a form that will give the requisite strength with a smaller amount of metal than as at present constructed, and thereby cheapen the cost.

It consists in constructing the springs of corrugated metal, and arranging the plates or strips so as to take the strain in the direction of the breadth of the same.

Figure 1 represents a side elevation of an elliptical spring constructed according to my improvement.

Figure 2 represents a side elevation of an arched spring.

Figures 3, 4, and 5 represent plan views of various forms of springs.

Similar letters of reference indicate corresponding parts.

I propose to corrugate the plates or strips of metal of which the springs are to be formed, in order to give them, when arranged as represented in the drawings, so as to take the strain in the direction of their breadth,

a sufficient amount of resistance laterally to maintain them in the right position, and also to increase their strength in the direction of the strain due to the weight they are intended to bear.

They may be made of one or any other number of strips or plates, and when more than one is used, they may be riveted together, as shown at *a*, and the ends may be pivoted together in any suitable manner, as represented in fig. 1, or provided with suitable bearings, when designed to be used, as in figs. 2 and 4.

By this arrangement, I am enabled to construct springs, suitable for all purposes for which the ordinary elliptical or arched springs are used, of very great strength, with a much smaller amount of metal than is now used, as will be readily understood.

My improved springs may be hardened and tempered as other springs made of steel are.

Having thus described my invention,

What I claim as new, and desire to secure by Letters Patent, is—

Elliptical or arched springs, made of corrugated sheets or plates, arranged as herein shown and described, substantially as and for the purpose set forth.

The above specification of my invention signed by me, this 17th day of August, 1868.

FR. CAJAR.
